DAVID HATHAWAY, OF TROY, NEW YORK, ASSIGNOR TO FULLER, WARREN, AND COMPANY, OF SAME PLACE.

Design No. 2,746, dated August 13, 1867.

DESIGN FOR A STOVE-PLATE.

The Schedule referred to in these Letters Patent and making part of the same.

TO ALL WHOM IT MAY CONCERN:

Be it known that I, DAVID HATHAWAY, of the city of Troy, in the county of Rensselaer, and State of New York, have invented or produced a new and original Design for Plates of a Cooking-Stove, of which the following is a full and exact description, reference being had to the annexed photographs of a side of a cooking-stove having my said design.

The ornamental design for the large door-plate A consists of the central ornament d and the spiral border ornament e, both shaped and arranged on the plane-surface panel of the door as shown in the annexed photograph. The ornamental design for the small door-plate B consists of the centre ornament f and border ornament g, all shaped and arranged on the plane panel of that door, so as to appear as represented in the aforesaid photograph; and the ornamental design for the side plate C consists of an ornamental rectangular panel formed by the bead moulding h and ornament i, all shaped and arranged on the lower part of the forward portion of the side plate, as shown in the accompanying photographs.

What I claim as my invention or production, and desire to secure by Letters Patent, is—
The above-described ornamental design for the plates A, B, and C of a stove.

DAVID HATHAWAY.
